UNITED STATES PATENT OFFICE

156,493

COMBINED CIGARETTE LIGHTER AND CONTAINER FOR LIGHTER FUEL

Rose R. Eratico, Long Island City, N. Y.

Application December 20, 1948, Serial No. 150,276

Term of patent 14 years

(Cl. D48—27)

To all whom it may concern:

Be it known that I, Rose R. Eratico, citizen of the United States of America, and residing at Long Island City, N. Y., United States of America, have invented a new, original, and ornamental Design for a Combined Cigarette Lighter and Container for Lighter Fuel, of which the following is a specification, reference being had to the accompanying drawing, forming part thereof.

In the drawing:

Fig. 1 is a side elevational view of a combined cigarette lighter and container for lighter fuel, showing my new design, and

Fig. 2 is a top plan view thereof.

I claim:

The ornamental design for a combined cigarette lighter and container for lighter fuel, substantially as shown.

ROSE R. ERATICO.
